UNITED STATES PATENT OFFICE.

ERNEST DE GAY, OF LIVINGSTON HEIGHTS, VIRGINIA.

RIBBON CLEANER AND DRIER.

1,304,275.

Specification of Letters Patent. Patented May 20, 1919.

Application filed September 11, 1918. Serial No. 253,656.

To all whom it may concern:

Be it known that I, ERNEST DE GAY, a citizen of the United States, residing at Livingston Heights, in the county of Alexandria 5 and State of Virginia, have invented certain new and useful Improvements in Ribbon Cleaners and Driers, of which the following is a specification.

This invention relates to power die stamping presses and more particularly to a wiping ribbon cleaner therefor.

The primary object of this invention resides in the provision of a combination of elements to be attached to any form of power 15 die stamping press for cleaning the wiping ribbons thereof.

Another object of this invention resides in the provision of means for cleaning the wiping ribbons used on power die stamping 20 presses so that said wiping ribbons can be used a number of times.

A still further object of this invention resides in the provision of means whereby the wiping ribbons of power die stamping 25 presses will be washed and dried after having performed their functions.

A still further object of this invention resides in the provision of means for cleaning the wiping ribbons of power die stamping 30 presses and recovering the ink collected thereon for further use.

With these and other objects in view, this invention resides in certain novel features of construction and arrangement of elements 35 to be more particularly set forth in the specification herewith and pointed out in the appended claim, it being understood that the right is reserved to resort to any changes in construction as come within the scope of 40 the claim.

In the accompanying drawing,

Figure 1 is a plan view of a conventional illustration of a power die stamping press showing the elements of this invention attached thereto.

Fig. 2 is a longitudinal sectional view thereof.

Fig. 3 is an enlarged side view of the washer and drier.

Fig. 4 is a similar view of the scraper frame.

Fig. 5 is a rear view of the washer and drier.

Fig. 6 is a similar view of the scraper.

Fig. 7 is a detail horizontal sectional view of the wiper.

In the present embodiment of this invention the letter A designates a conventional illustration of a power die stamping press, which, in this instance, consists of a feed reel, B, a winding reel C, a wiping pad D, an ink fountain E, wiping ribbon guides F, in the form of rollers and brace rods G. The aforesaid elements being parts of but one form of a power die stamping press, which 60 may be rearranged without affecting the operation of this invention, as certain minor departures from the present disclosure will be necessary to permit this invention to be applied to different types of power die 65 stamping presses.

Securely fastened adjacent to the wiping pad D, of the power die stamping press on certain of the brace rods G, is a scraper frame, 5 which supports a plurality of guide 75 rollers 6, for directing the wiping ribbon H, in contact with an adjustable scraping blade, 7 carried between the side members 8, of the scraper frame 5.

Attached on the power die stamping press 80 A remote to the wiping pad thereof, is the frame 9 of a paper washer and drier which consists of guide rollers 10, 11 and 12 and adjustable scrapers, 13 and 14, arranged on opposite sides of the wiping ribbon and 85 a heated pad 15, for engagement with the wiping ribbon, to dry the same after being washed by passing around the lower roller, 11, which is submerged in a washing fluid in the reservoir 16.

In the present instance, the reservoir consists of two compartments 17 and 18, having a partition 19, therebetween of less height than the sides of the reservoir, so that the heavier particles of the ink that is removed 90 from the wiping ribbon by the scraper, 14 will be deposited in the compartment 18, and the fluid thereof will be permitted to flow over the partition as the compartment 18 is 95 filled.

Beneath the scraper 7, is suitably secured a gutter, 20, for delivering the ink that is initially removed from the wiping ribbon by the scraper 7, to the ink fountain for further use.

With the aforesaid elements, arranged in operative positions, the wiping ribbon is passed beneath the wiping pad D, from the feed reel B, and directed in contact with the scraper blade 7 by the rollers 6, after 110 which it is directed into the reservoir 16, by the rollers 10 and 11, and after being

submerged in the fluid in said reservoir, the wiping ribbon is directed in contact with the scrapers 13 and 14, past which it is drawn over the roller 12 and heated pad 15, located between said upper roller and said winding reel, to the winding reel C.

Adjacent the roller 11 and slidable on a shaft 39 is a reciprocating wiper 25, which is manipulated in this instance by meshing 10 gears 26 and 40, on shafts 27 and 39 of the roller 11 and wiper 25 respectively. The gear 40 is loose on the shaft 39 and carries a cam 28 which is adapted to engage the adjacent surface of the wiper 25 so that as the loose 15 gear 40 on the wiper shaft 39 is rotated by the gear 26 on the shaft 27, the cam will cause the wiper to compress the spring 41 at its opposite end and upon the disengagement of the cam the spring will return the 20 wiper so that the cam can again perform the same function. As shown the adjustable scrapers 13 and 14 are located above the reciprocating wiper 25.

With the above mechanism it is possible 25 to thoroughly remove particularly all the ink left on the ribbon after being bathed in the fluid within the reservoir 16.

With this invention fully set forth, it is manifest that a wiping ribbon cleaner for 30 power die stamping presses is produced which is cheap to manufacture, easily at-

tached to any type of press and readily adapted to prolong the life of the wiping ribbon.

Having thus described this invention, 35 what I claim is:

The combination with a die stamping press including a winding reel and a feed reel, of a ribbon wiping and cleaning mechanism comprising a frame, a lower guide 40 roller held in said frame, a shaft adjacent to said roller, a cam gear loose on said shaft, a wiper mounted for reciprocatory movement on said shaft, a reservoir located in said frame, said roller being located in said 45 reservoir, a gear held to said roller and in mesh with said cam gear, a spring on said shaft to force said wiper against said cam gear, an upper guide roller, an adjustable scraper located above said wiper, a second 50 adjustable scraper located above said first mentioned adjustable scraper, and a heated pad located between said upper roller and said winding reel, whereby a wiping ribbon unwinding from said feed reel to said winding reel is made to pass over said lower roller, and against said reciprocating wiper between and against said adjustable wipers, over said upper roller and pad, and upon 55 said winding reel.

In testimony whereof I affix my signature.
ERNEST DE GAY.
